UNITED STATES PATENT OFFICE

136,066

DESIGN FOR A KNOCKDOWN TOY CRADLE

James K. Makrjanies, Longmeadow, Mass., assignor to National Paper Box Co. Inc., West Springfield, Mass., a corporation of Massachusetts

Application March 15, 1943, Serial No. 109,756

Term of patent 7 years

To all whom it may concern:

Be it known that I, James K. Makrjanies, a citizen of the United States, residing at Longmeadow, in the county of Hampden and Commonwealth of Massachusetts, have invented a new, original, and ornamental Design for a Knockdown Toy Cradle, of which the following is a specification, reference being had to the accompanying drawing, forming part thereof.

The figure is a perspective view of a knockdown toy cradle showing my new design.

I claim:

The ornamental design for a knockdown toy cradle, as shown.

JAMES K. MAKRIJANIES.
